(57) **CLAIM**

The ornamental design for an airplane lavatory, as shown and described.

DESCRIPTION

FIG. 1 is a front, right perspective view of an airplane lavatory showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a sectional view taken along lines 8-8 shown in FIG. 2;

FIG. 9 is a sectional view taken along lines 9-9 shown in FIG. 2;

FIG. 10 is a sectional view taken along lines 10-10 shown in FIG. 6;

FIG. 11 is a sectional view taken along lines 11-11 shown in FIG. 6;

FIG. 12 is a sectional view taken along lines 12-12 shown in FIG. 6;

FIG. 13 is a sectional view taken along lines 13-13 shown in FIG. 6;

FIG. 14 is a front, left perspective view showing an interior part thereof;

FIG. 15 is a front, left perspective view showing the interior part thereof in a state where a seat cover is opened; and,

FIG. 16 is a front, left perspective view showing the interior part thereof in a state where a seat and a seat cover are opened. The broken lines shown are included for the purpose of illustrating the unclaimed portions of the airplane lavatory and form no part of the claimed design.
